PAUL GANGLER, OF ESSLINGEN, GERMANY, ASSIGNOR TO THE FIRM FR. HESSER MASCHINENFABRIK-AKTIENGESELLSCHAFT, OF STUTTGART-CANNSTATT, GERMANY

DEVICE FOR CONTINUOUSLY DRYING PAPER WEBS PROVIDED WITH AREAS OF VARNISH

Application filed March 8, 1929, Serial No. 345,335, and in Germany March 17, 1928.

The invention relates to improvements in devices for continuously drying areas of varnish applied to webs of paper. Such webs of paper are, for instance, used to manufacture envelopes or similar wrappers, which by the 5 application of a suitable varnish or the like are provided with transparent portions, called windows.

The object of the invention is to provide a 10 device adapted to treat the web of paper, to which such windows have been applied in a suitable machine, in such a manner that the varnished portions of the web of paper are in a continuous operation dried hard, i. e. so that the dried varnish is no longer adhesive. 15 The paper web thus treated may then be directly fed into further machines adapted to convert it into envelopes or be wound up into a reel to be stored until required.

20 In the accompanying drawings, two embodiments of the invention are shown by way of example.

In the drawings are

25 Fig. 1, a side-elevation of the improved device,

Fig. 1^a, a part of Fig. 1 in different position,

Fig. 2, a plan of Fig. 1, but with the paper web omitted for the sake of clearness, and

30 Fig. 3, a side-elevation of a modification.

Referring to Fig. 1 of the drawings, it will be observed that the web of paper coming from the varnish applying or window producing machine is introduced into the improved 35 drying device at the left-hand side from below. On the outside of the web 1 areas of varnish 1^a are provided which are to be dried in the device. The web rests upon a quadrant 24 provided with lateral guides 40 and is in the form of spirals guided over sets of rollers through the frame-like drying casing 50 in such a manner that it is supported on its inner side only, where no varnish has been applied to the paper. The web is passed 45 first over the rollers 4^a, 5^a—9^a, then in a second spiral over the rollers 4^b, 5^b—9^b, in a third spiral over the rollers 4^c, 5^c—9^c, in a fourth spiral over the rollers 4^d, 5^d—9^d, and in a fifth spiral over the rollers 4^e, 5^e—9^e. 50 From the roller 9^e the paper web 1 passes

over the roller 10 and then issues from the casing 50 over a roller 11 and then forms a loosely hanging loop 1', whereupon the web 1 is again caught in a manner described later on and after a few turns guided to a reel or other winding up device. This procedure 55 serves to give the web time to cool down by the radiation of the heat absorbed in the casing into the ambient air or by the aid of artificial means, such as fans, blowers or the like, so that the varnish producing the windows becomes hard after the drying and the window does not stick to the paper when the web is wound up into a reel. The loop 1' also 60 serves to equalize any speed fluctuations. A 65 further object of the loop is to align the web again should it have deviated laterally during its passage through the casing, which in view of the considerable length can never be avoided altogether. In this way it is possible 70 to obtain reels which are correctly wound up at both sides.

The guide rollers 5^a—5^e, 7^a—7^e, 8^a—8^e, 9^a—9^e and 10 in the drying casing run idle. 75 They are entrained by the friction of the web 1. The rollers 4^a—4^e are driven at equal speeds by means of spur wheels 4^{a'}—4^{e'} mounted on their spindles and coupled by the transmission wheels 4^{a''}—4^{e''}. One of the spindles, for instance the spindle 4' of the roller 4^d, is driven from outside by the belt 31 and the pulley 32, for example. To impart 80 to the web 1 within the casing so much draw or tension that it deviates laterally from its proper path within the permissible limits 85 only, the drive of the rollers 6^a—6^e in the right-hand upper corner of the drying casing, which may be effected for instance by suitable pulleys, is so designed that the circumferential speeds of these rollers diminish 90 stepwise from the inside towards the outside. The pulley 33 mounted on the spindle 4' drives the pulley 36 on the spindle 35 by means of the belt 34. On the axles of the rollers 6^a—6^e are mounted the grooved belt 95 pulleys 6^{a'}—6^{e'}, and on the axles 35 is mounted the grooved drum 37 with 5 grooves, which correspond with the pulleys 6^{a''}—6^{e''}. By the round straps 6^{a''}—6^{e''} are driven the rollers 100 6^a—6^e, and the diameters of the pulleys

6^a—6^c are so dimensioned that the circumferential speed of the roller 6^a is slightly higher than the circumferential speed of the rollers 4^a—4^c revolving at the same circumferential speeds. The circumferential speed of the roller 6^b is again slightly higher than that of the roller 6^a, that of the roller 6^c again higher than that of the roller 6^b, that of the roller 6^d again higher than that of the roller 6^c, and 10 that of the roller 6^e again slightly higher than the circumferential speed of the roller 6^d. The above mentioned roller 11 is driven from the pulley 41 mounted on the driving spindle 4' by means of the strap 11" and the pulley 11' mounted on the spindle of the roller 11 in such a manner that its circumferential speed 15 is again slightly higher than the circumferential speed of the roller 6^e. For increasing the circumferential friction, a friction roller 20 11^a may idly rest upon the roller 11. In a similar way, friction rollers may ride upon the rollers 6^a—6^e to increase the circumferential friction, if desired. In this manner, the paper web 1 passes under uniform 25 tension through the drying casing, without the danger that the paper may be torn by an excessively strong pull being exerted upon it.

In the modification of the device illustrated in Fig. 3, the web of paper 1 is guided through 30 the drying casing 50^a in long loops 51^a—51^e. These loops are supported by the guide rollers 52^a—52^e, the spindles of which are driven by the sprocket wheels 54^a—54^e mounted upon them, by means of the chain 55. For driving 35 the spindle of the roller 52^a there is provided a belt 56 and the pulley 57 mounted on the spindle of the roller 52^a. To obtain the necessary friction, the idle friction rollers 53^a—53^e ride upon the guide rollers 52^a—52^e. 40 To prevent swinging of the loops 51^a—51^e when the web 1 runs through the drying casing 50^a, they are supported on the inside by special guide ways which may, for instance, consist of the round rods 60.

45 For drying the windows or transparent areas produced by the application of the varnish to the web 1, there are provided in both embodiments of the device electrical heating elements, for instance, the number, 50 arrangement and heating action of which may be regulated so that the varnish is dried to the desired extent. In Fig. 1 there are, for instance, provided a plurality of heating elements A, which radiate heat against the inside 55 of the web 1, which has just entered the casing, in the direction indicated by the arrows. In a similar manner, heating members A' having a downward action are provided in the bottom part of the casing. Other heating 60 elements B, B' are provided to heat the second spiral of the paper web 1. In Fig. 3 heating elements A are provided at the inside of the paper web.

To accelerate the drying process, the drying casing may be completely enclosed with

the exception of the slots for introducing and withdrawing the web 1, and air may either be blown into the casing as indicated at 50 in Figure 1 or be ejected from it as indicated at 51 in Figure 1. The casing may, however, 70 also be left open, and a number of propellers or fans may be provided to effect the desired circulation of the air for instance through the pipes 52 and 53 indicated in Figure 3. The arrangement of the heating elements between the individual webs takes care that the heat generated by the said elements is almost exclusively imparted to the web and to the air surrounding the web from both sides, so 75 that the heating action attains a high efficiency. 80

The reeling and reel changing device illustrated in Figs. 1 and 1^a may be used for both embodiments shown. It will be readily understood that the drying device when first started will attain only after some time the steady work giving a good result. This reeling and reel changing device is, therefore, so designed that the reeling of the paper web, the removal of the finished reel and the transfer to a new reel take place in such a way that during these operations the web can run continuously and at unchanged speed through the casing, so that the steadiness of the service once attained will not be interrupted. 85

90 As already described, the web 1 issuing from the casing forms the loop 1'. The right-hand portion of the loop is turned into the horizontal plane by means of a curved track upon which the web 1 gets rest by its own gravity. In the example illustrated, the curved track consists of circular rods 12, which at their ends are loosely supported in the rails 13^a, 13^b. The accurate lateral position of the paper web 1 is ensured by the lateral guide bars 13', 13''. To obtain the tension necessary for winding up the web, a brush 25 or the like may be provided, if desired, which increases the friction of the web 1 along the curved track. The web 1 is 100 led over the rollers 14, 15, 15^a, then over the roller 16, which is adapted to revolve upon the spindle 16^a, and over the roller 15^b, which is journaled in the arms 17^a', 17^b' of the connecting links 17^a, 17^b, and is finally laid 105 around the roller 18 connected with the spindle 18^a, which in its turn is with its ends journaled in the said connecting links 17^a, 17^b. The links 17^a, 17^b are loosely rotatable on the spindle 16^a. The roller 18 or the spindle 110 18^a respectively is, for instance, driven by a belt drive in the following manner: A pulley 42 mounted on the spindle 4', Fig. 2, drives the intermediate shaft 44 by means of the belt 43, from which the spindle 16^a is 115 driven by means of the belt 45 and the pulley 46^a. By means of the chain wheel 46 keyed to the spindle 16^a, the chain 47 and the chain wheel 48 mounted on the spindle 18^a, the drive 120 is transmitted to the spindle 18^a, whereby 125 130

without interfering with the drive, the roller 18 can be moved up and down around the spindle 16^a.

The reeling of the web is effected by means of the spindles 19^a, 19^b, 19^c, which carry in the well-known manner the paper tubes 20^a, 20^b, 20^c, upon which the paper web 1 is to be wound up in succession. The spindles 19^a, 19^b, 19^c are removably and rotatably journaled in the two side spiders 22^a, 22^b, which are keyed to the spindle 21. The spindle 21 is adapted to revolve in the two end pedestals 23^a, 23^b. In Fig. 1, the reeling spindle 19^a just occupies its working position. At the initial starting of the reeling, the web 1 is led unto the roller 16 in the manner described and passed around the raised, but for the time being still stationary, roller 18. The paper tube 20^a has been provided with some glue before it has been placed into the working position. Now the roller 18 is lowered into the position indicated by dotted lines upon the tube 20^a and rotated by switching in the drive. The revolving roller 18 puts the tube 20^a in rotation due to the friction set up by its weight, the web 1 is fed forward, and as its end is glued to the tube 20^a, it is wound up on the tube. The circumferential speed of the paper reel thus produced remains constant owing to the nature of the drive. As the diameter of the reel 2 increases, it gradually raises the roller 18. When the reel 2 has attained the desired diameter, the spindle 21 is turned through an angle of 120° in a clockwise direction, either by hand or by a suitable mechanism which is automatically set into operation if the reel 2 has got the desired diameter, for instance by means of a feeler operated by the reel and controlling the operation of the turning device for spindle 21. In this way, the roller 18 is lowered and comes automatically to rest upon the tube 20^b already previously provided with glue. This is the position illustrated in Fig. 1. The web 1 is, therefore, stuck instantly to the tube 20^b, and the winding up of a new paper reel on the tube 20^b is started at once. By the strong pull exerted thereby to the web, the latter will be severed automatically between the reel 2 and the tube 20^b, for instance at the point 27 in Fig. 1^a. Of course, the web may be also severed by hand or by a suitable cutting mechanism. The reel 2 can be finished at leisure and removed from the device, and the spindle 19^a can be provided with a fresh paper tube 20^a. If the paper reel on the paper tube 20^b has nearly attained its desired diameter, the paper tube 20^c is provided with glue. At the proper movement, the same cycle of the paper reel change is then repeated.

To prevent that in consequence of any slip of the paper web 1 the loop 1' will become excessively large or small, provisions have been made to change the speed of the inter-

mediate shaft 44 accordingly, which may, for instance, be effected by providing tapering belt drums on the spindles 4' and 44 and by a corresponding displacement the belt 43 on the said drums.

Instead of winding the web into a reel for storage, it may from the herein described device be directly conducted to the machine for further treatment, for instance to a machine for manufacturing envelopes with windows or similar wrappers.

Various changes may be made without departing from the spirit of my invention.

I claim as my invention:

1. In a device for continuously drying paper webs provided with areas of varnish, in combination, a drying chamber, means for guiding a web of paper within said chamber in spirals running from outside towards the inside, said guiding means comprising sets of driving rollers and sets of idle rollers, and means to turn the driving rollers of certain sets with various speeds increasing from the outside towards the inside.

2. In a device for continuously drying paper webs provided with areas of varnish, in combination, a drying chamber, means for guiding a web of paper within said chamber in spirals running from outside towards the inside, said guiding means comprising sets of driving rollers and sets of idle rollers, a sideways guiding track in front of said chamber adapted to catch the paper web and lead it to the outermost roller of the first set of driving rollers running at equal speeds and arranged adjacent to the entrance of the said web, and means to drive the rollers of a subsequent set of driving rollers so that the outermost roller is revolved faster than the rollers of the said first set of driving rollers and the remaining rollers of said subsequent set of driving rollers are revolved towards the inside stepwise faster than the said outermost roller.

In testimony whereof I have affixed my signature.

PAUL GANGLER.
